UNITED STATES PATENT OFFICE.

JOHN H. BURHOP, OF HOT SPRINGS, ARKANSAS.

REFRIGERATOR SHOW-CASE.

1,248,449.

Specification of Letters Patent. Patented Dec. 4, 1917.

Application filed January 22, 1916. Serial No. 73,662.

To all whom it may concern:

Be it known that I, JOHN H. BURHOP, a citizen of the United States, residing at Hot Springs, in the county of Garland and State of Arkansas, have invented a new and useful Refrigerator Show-Case, of which the following is a specification.

The present invention relates to an improved show case, and means for cooling the same whereby meats and other perishable food may be displayed and at the same time cooled to prevent deterioration thereof.

An object of the invention is to provide a show case or show case counter adapted to removably inclose a bottom and refrigerating pans whereby perishable articles can be preserved, and the parts may be easily separated to be cleaned.

Another object of the invention is to provide a relatively small ice compartment for the reception of cracked ice and salt, or other suitable cooling agent, and which is of such form, and is so assembled that it may fit within the body of the case and rest directly on the bottom so as to cool the interior of the case.

Other objects and advantages of this invention will be brought out in the following specific description of the present preferred embodiment of the invention, the same being disclosed in the accompanying drawings, wherein

Figure 1 is a perspective view, looking at the rear side, of the improved refrigerator show case.

Fig. 2 is a longitudinal vertical section, taken centrally through the show case.

Fig. 3 is a transverse central section through the same.

Fig. 4 is a detail perspective view of the body of the show case, having the bottom and other parts thereof removed.

Fig. 5 is a detail perspective view of the upper ice pan, which also supports the food in the case.

Fig. 6 is a detail perspective view of the lower ice pan adapted to contain the cracked ice and being of such size as to receive therein the upper pan, shown in Fig. 5.

Fig. 7 is a detail perspective view of the bottom of the improved show case.

Referring to the accompanying drawings, wherein like parts are designated by similar characters of reference throughout the several views, 10 designates the bottom of the improved show case. This bottom 10 may be

made of any suitable material, but is preferably of wooden construction, as shown to advantage in Fig. 7, and is provided near one end with a drainage opening 11. The bottom 10 is adapted to rest on a counter, or other suitable support, and is adapted to receive thereover an inclosing body 12, shown to advantage in Fig. 4, which is provided in at least three sides, and in its top with transparent panels to admit of the uninterrupted inspection of the contents of the show case, from practically any side thereof. The body 12 is preferably of the usual wooden construction, and is provided with a pair of laterally sliding closure doors 13, which close the rear side of the case, and which may be slid from side to side in order to gain access to either end of the body 12. The lower edge of the body 12 is provided with a base strip or head 14, which, as shown to advantage in Figs. 2 and 3, is provided in its under side with a recess 15 adapted to receive therein, the marginal edge of the bottom 10 when the body 12 is placed over the bottom. If desired, suitable fastening means, such as the winged bolts 16, may be threaded through the base strip 14 at the opposite sides of the body 12, and be screwed into the marginal edge of the bottom 10, in order to hold the latter securely to the body.

The means for cooling the interior of the show case comprises a pan 16^a formed by a flat bottom and an upstanding marginal flange thereabout, and being of a configuration adapted to fit loosely in the lower end of the body 12, as shown in Figs. 2 and 3. This pan 16^a is adapted to contain a quantity of ice and salt, or other suitable refrigerating substance. To admit drainage of the pan 16^a, the same is provided with an opening near one end thereof closed by a removable stopper 17. The opening in the pan 16^a registers directly over the opening 11 in the bottom 10, so that liquid accumulations in the pan 16^a may be drained out through the bottom of the case. The ice, or other cooling agent, placed in the pan 16^a is covered or inclosed by means of an upper pan 18, which is of the same configuration and formation as the pan 16^a and is slightly reduced in size so as to fit into the top of the pan 16^a, and has its marginal flange of less depth, so that the upper edges of the upper and lower pans lie flush when they are placed one within the other. When desired, the pan 16^a may be provided in its corners with supports or

stops 19 upon which the upper pan 18 may rest, and so as to hold the pan 18 in a true horizontal position.

In Figs. 4 to 7, inclusive, of the drawings, 5 the four principal parts of this improved show case are shown in separated position, but in registering relation, one above the other. In assembling the show case, it is only necessary to place the bottom 10 upon 10 a suitable horizontal support, and place the ice pan 16^a upon the bottom in its proper registering position. The ice pan 16^a is now filled to the desired height with cracked ice mixed with salt, or any other desired 15 cooling agent, and the upper pan 18 is then inserted into the top of the pan 16^a, to thus provide a closed compartment for the ice, as shown to advantage in Figs. 2 and 3. If desired, the perishable food may now be placed 20 within and upon the pan 18 and arranged therein for display. The body 12 may now be grasped and placed down over the ice receptacle, and fitted onto the bottom 10. The wing bolts 16 are now turned so as to 25 lock the bottom to the body 12. When it is desired to readjust or remove portions of the food stuff without disassembling the show case, it is only necessary to slide the doors 13 to one side, or the other, to gain access 30 to the interior of the body 12, through the rear side thereof.

The perishable food stuff is usually placed in porcelain receptacles and set in the pan 18, which pan is relatively shallow, so that 35 the food may be very easily examined, and is not surrounded by a relatively deep enclosure.

When it is desired to clean and polish the glass panels in the body 12, and to clean the 40 interior thereof, it is only necessary to raise the body 12 up from the bottom 10 clear of the ice pans and the goods on display without disturbing the adjustment or arrangement of the same.

45 It is, of course, understood that various changes and modifications may be made in the above described embodiment of the invention, without departing from the spirit thereof, and being restricted only by the 50 scope of the following claims.

What is claimed is:—

1. A refrigerator show case comprising a bottom, a pair of pans mounted on the bottom, the lower pan being adapted to retain a cooling agent therein, and the upper pan 55 forming a cover for the lower pan and serving as a support for the articles in the show case, and a transparent body open at the lower side, and fitted down over said pans to inclose the same, and having its lower 60 edge detachably engaging said bottom.

2. A refrigerator show case comprising a bottom, a pan mounted on the bottom for the reception of chopped ice, a second pan inclosing the top of the first pan and providing a support for the contents of the show case, the marginal edge of the bottom projecting beyond said pans, and a transparent body open at the lower side, fitted down over 65 said pans and having a head detachably engaging the marginal edge of said bottom 70

3. A refrigerator show case comprising a bottom, a pair of interfitting pans mounted on the bottom and adapted to receive therebetween a cooling agent and provide a support, a transparent body fitted down over 75 said pans to inclose the same and engaging said bottom, and wing bolts for detachably securing the body to said bottom.

4. A refrigerator show case comprising a 80 bottom having an opening through one end thereof, a pan fitting on the bottom and having an opening therethrough registering with the opening in the bottom, said pan being adapted to receive a quantity of ice, 85 a stopper engaging in the opening in the pan to retain the melted ice therein, a second pan fitting in the upper side of the first pan and adapted to inclose the ice and provide a support for goods displayed, and a 90 transparent body detachably fitted over said pans and said bottom.

In testimony that I claim the foregoing as my own I have hereto affixed my signature in the presence of two witnesses.

JOHN H. BURHOP.
